JAMES C. ROBERTS, OF ADAMSTOWN, MARYLAND.

Letters Patent No. 60,789, dated January 1, 1867.

IMPROVEMENT IN GRINDING-MILLS.

The Schedule referred to in these Letters Patent and making part of the same.

TO ALL WHOM IT MAY CONCERN:

Be it known that I, JAMES C. ROBERTS, of Adamstown, in the county of Frederick, and State of Maryland, have invented certain new and useful improvements in Regulators for Grinding-Mills; and I do hereby declare the following to be a full, clear, and exact description of the same, reference being had to the accompanying drawings, making a part of this specification, in which—

Figure 1 represents a side elevation of the mechanism for regulating the stones, as also the feed of the mill.

Figure 2 represents a transverse section through the same, with portions of the mechanism dotted in, which would not otherwise appear in the section.

Figure 3 represents a section through a portion of the mechanism which will be hereafter more fully referred to.

Similar letters of reference where they occur in the separate figures denote like parts of the apparatus in all the drawings.

My invention relates to a self-acting mechanism by which a grinding-mill is regulated so as to do uniform work, whether the water or other power that drives the mill varies or not. This mechanism is operated from any moving part of the mill gear, and is actuated through a governor which is sensitively affected by every change of speed in the mill, and raises or lowers the runner, as well as increases or diminishes the feed, as may be required for the quality of grain used, or the kind of flour or meal to be produced.

To enable others skilled in the art to make and use my invention, I will proceed to describe the same with reference to the drawings.

A represents a frame upon which the grinding-stones or buhrs are placed. From a pulley, B, on the spindle C of the runner, an endless belt, D, passes to and around a pulley, E, on the governor-shaft, F, and by which said shaft is driven. The governor-shaft F, as also the regulating mechanism which the governor controls, is placed on a frame or stand, G, in any convenient position in the mill; it is shown in the drawings in close proximity to the grinding-stones, but may be placed remote therefrom if so preferred. On the shaft, F, there is a bevel gear, H, which works a similar gear, I, supported in the stand G by a shaft or journal, a, which turns with it. On the shaft or journal a there is a crank-wheel, b, in which a wrist-pin, c, is placed, and this wrist-pin works in a slot, d, made in the lower end of a vibrating arm, J, that rocks or moves on the shaft K. The shaft K has secured on it, near the vibrating arm J, a ratchet-wheel, L, with radial or ordinary cog teeth upon its perimeter, so that a double pawl, or rather two pawls, e e', may alternately work in it, as the case may be, so as to turn said ratchet, and of course the shaft K on which it is fastened. When one pawl is thrown into action, the opposite one is thrown out, as will be hereafter explained. On the opposite end of the shaft K from the ratchet-wheel L, there is a bevel spur or pinion, M, that works into a bevel gear, N, the shaft of which is made into a nut to work on the screw rod O connected with the bridge-tree P, on which the spindle C is supported, the shaft of the bevel gear N being supported in a bracket, Q, fastened to the stand G.

The bridge-tree rod O, after passing through the hub or nut of the bevel gear N, extends upward, and is connected at f to the short arm g of a beam, R, that is pivoted to a down-hanger, S, attached to the stand G. On this beam R, a carriage, T, is caused to move in one direction or the other, as the case may be, by a mechanism to be presently described, said carriage having a poise or weight, U, suspended to it, which weight is made capable (by the opening through it) of being added to or taken from, by movable pieces of metal laid in or taken from said opening. Towards the end of the beam most remote from its fulcrum at S, a rod, h, is attached, which extends downward, its lower end being forked so as to straddle a groove made in the shaft K, the groove allowing the rod h to freely move in a vertical direction, but preventing it from moving laterally. On the rod h, between the beam R and shaft K, there is an arm, i, adjustable thereon, but fastened after it is adjusted, said arm having a curved slot, J, in it, in which a crank, K, that rocks the two pawls e e', works, putting one or other into and out of action with the ratchet-wheel L, as the speed and feed of the mill may require to keep it at a uniform grade of flour. The extreme end of the beam R has a rod, l, connected to it which extends upward, and is forked so as to straddle a screw-shaft, V, and be guided vertically and controlled laterally by said shaft.

The upper end of the vibrating arm, J, has a segmental rack, m, made on it, which works into a similar segment, n, on the bottom of a vibrating arm, W, suspended to the shaft, V, so that it can move independent of the movement of said shaft. The vibrating arm, W, has pivoted to its upper end two pawls, o o', one or the other

of which, as the case may be, is in action with a ratchet-wheel, X, fastened to the screw-shaft, V, and moves said shaft in the direction in which the pawl in action points. These pawls, o o', are thrown in or out of action as follows: A crank, p, on the pawl-shaft projects into a curved slot, q, of an arm, r, that is adjustably connected to a rod, s, which in turn is pivoted to a beam, Y, supported in a pillar, t, on the frame or stand, G. The end, u, of the beam, Y, is forked and straddles a collar or sleeve, v, to which the links w w of an ordinary fly ball governor, Z, are attached, so that the speed of the runner or movable stone of the pair, through its spindle, gives motion to the governor-shaft. The governor-shaft by its motion gives motion to the governor, Z, and the raising or lowering of the governor arms raises or lowers the free end of the beam, Y, and the beam in turn raises or lowers the rod s, and causes its arm, r, to move the crank p and throw one of the pawls into action and the other out of action with the ratchet X, as the case may be, and change the motion of the screw-shaft V accordingly.

On the screw-shaft V there is a sleeve, x, on which a lever, y, is pivoted, said lever having on one of its ends a tooth, 1, that takes into the thread of the screw, and the other end of the lever may have a spring under it to hold said tooth to the screw, and yield when necessary to shift the sleeve x on the screw-shaft. From the lower side of the sleeve x a rod, z, projects downward, and enters a hole in the carriage, T, so that as the sleeve moves along on the shaft, to the right or to the left, as the direction in which the shaft for the time being is moved by the pawl which may be in action may determine, the carriage, T, and weight, U, suspended to the carriage will move it on the beam, R; and that the beam may tip or yield to the weight as it is moved along on it, the rod connection z between the sleeve and the carriage must be such as not to prevent the beam from acting by the counter, over, or under poise of the weight upon it. The moving of this weight on the beam, R, raises or lowers the rod O, and the rod O raises or lowers the bridge-tree, P, which latter in turn raises and lowers the runner or moving stone of the pair of grinding-stones, bringing it nearer to or moving it farther from the bed-stone, as the speed and feed of the mill may require to turn out the standard of flour or meal for which the mill is set or regulated, and this, too, whether the head of water or other motive power which drives the mill, falls or not, and without the attention of any one. The screw-shaft V works into a worm-wheel, 2, that is arranged on a screw-shaft, 3, (see fig. 3,) and to this screw-shaft, 3, a lever, 4, (see fig. 2,) is connected, which has its fulcrum at 5, and has a tube, 6, at its end, which connects with the hopper tube 7, and with a common dish on the top of the runner spindle, so that the distance between the tube 6 and the dish (which latter is in common use) regulates the quantity of grain that is fed into the stones from the hopper. Thus the turning of the screw-shaft, V, which is regulated by the governor as to its direction, regulates the amount of feed or grain that is fed in to the stones. The governor is actuated by the speed of the runner, and thus through the governor the feed is made to correspond to the speed or motion of the runner. The runner, it will be observed, has two regulating devices—first, the weight on the beam works the bridge-tree, and the bridge-tree raises or lowers the stone; and secondly, the bridge-tree may be raised and lowered by the shaft K, bevel pinion M, and screw gear N, when the beam tips so as to throw in one or the other of the pawls, e e'; or in other words, the mill may be set for grinding a particular standard of flour early in the morning, when the head of water in the dam is high, and the speed and feed at their maximum. Now as the head of water falls and the speed becomes reduced, the feed is correspondingly reduced, so that the same quality of flour may be produced, though the quantity changes with the power that drives the stones. When the mill has been set for the grade of flour that is to be ground, it will run that grade so long as the power that drives the mill is unimpaired. But the moment, from any cause, the power or speed diminishes, then this regulating mechanism sets the runner and feed to continue that grade, but at the diminished speed and feed. And to notify the attendant when the runner and feed, one or both, have been adapted to the change of driving power, the bells 8, 9, will be rung by the moving of one or both of the pawl-wheels, L X, as the case may be.

I have shown one practical illustration of the operation of this self-acting regulating mechanism, but would state that I have myself made modifications of it, which, however, embrace the general characteristics of the invention. I do not, therefore, confine my invention to the arrangement of mechanism herein described and represented, as it may be used and arranged in many other forms and produce the same effect. The feed and set of a grinding-mill are increased and diminished, as at present arranged, by several causes, viz: by an increase of the head of water, or by throwing out of gear some of the machinery, which would give more power to the grinding-stones, and again by the decrease in the head of water, which is often caused by the rack choking up with leaves, or by the quantity of water in the dam being exhausted, or by throwing in additional gearing. My regulator compensates for any and all such causes, as well as for the expansion and contraction of the spindle or any changes in the motive power whether of water or steam.

Having thus shown how my invention may be used in connection with grinding-mills, and explained its object and characteristics, what I claim therein as new, and desire to secure by Letters Patent, is—

In combination with a governor operated from the mill-gear, a regulating mechanism operated through the intervention of a screw-shaft, a travelling poise and scale beam, and that will change and adapt both the feed and the set of the stones to the varying speed of the runner, caused by changes in the motive power, and thus produce a uniform grade of flour or meal, substantially as described.
